INTERNAL COMBUSTION ENGINE

Frank C. Best, Detroit, Mich., assignor to Packard Motor Car Company, Detroit, Mich., a corporation of Michigan

Application June 13, 1935, Serial No. 26,484

9 Claims. (CL 123—90)

This invention relates to improvements in the operating mechanism for the valves of internal combustion engines and is more particularly concerned with means for eliminating clearance and play in the mechanism in order to secure more efficient and quiet operation of the valves.

It has heretofore been proposed to employ take-up devices of the general character indicated, but such devices have not proven wholly satisfactory from a practical standpoint. Thus it is essential for satisfactory performance that such devices be capable of functioning properly over the extreme range of temperature established in actual use, that they be capable of withstanding the stresses resulting from high frequency impulses to which they are subjected when employed with modern high speed engines, and that they shall be of sufficiently small size and light weight to permit of use without adversely affecting the operation of conventional valve actuating mechanism or requiring material alteration of the design of such mechanism.

It is proposed by the present invention to meet those various requirements and to provide a small and compact device which is of light weight and which will function, for an indefinite period without any attention, to automatically regulate or eliminate clearance in the valve mechanism. In its more specific aspect the invention is concerned with the provision of a valve tappet which may be readily employed as a substitute for valve tappets or cam followers now commonly interposed between the cam shaft and the valve stem of poppet valves. It is a feature of the invention that the device, whether intended for use as a tappet or for association in some other way with conventional valve mechanism, may be readily assembled and sold as a complete unit.

It is a further object of the invention to provide a device of the character described in which a liquid medium is employed to oppose displacement of the working parts except when necessary for the purpose of taking up clearance in the valve mechanism, the construction preferably being such that the liquid may completely fill and be sealed within a closed fluid system, air being thus permanently excluded from the system so as to ensure uniformity of action.

It is a further object of the invention to provide a valve tappet which is preferably generally cylindrical in shape and of a length and diameter comparable to that of known non-adjustable or manually adjustable tappets, the working parts of the tappet being so arranged as

to occupy a portion only of the length of the tappet, whereby a roller or other anti-friction means for engagement with the operating cam may be utilized if desired.

A further object of the invention is to promote uniformity of action in devices of the character described by the provision of cooling means, whereby the plurality of devices required for the several valves of the engine may be maintained at substantially the same temperature. 10

The invention further contemplates an improved method of assembling a clearance take-up device of the type employing a non-compressible fluid or liquid, whereby air may be discharged and the introduction of air into the fluid system permanently and completely eliminated. The method of assembly is preferably such that an initial compensation for variation in spacing between the valve stems and the valve cams of internal combustion engines may be effected and precise similarity of function of the devices used with a plurality of valves may be thus ensured.

Further objects and features of the invention will be apparent from the following description taken in connection with the accompanying drawings, in which

Figure 1 is a sectional view through a portion of the valve mechanism of an engine illustrating the application of the invention to a valve tappet; 30

Figure 2 is a view partly in section of a portion of the structure shown in Figure 1 taken at right angles to that figure;

Figure 3 is a side elevation of an internal combustion engine illustrating the application of a cooling system to the valve tappets; 35

Figure 4 is a sectional view of a valve tappet illustrating a modified construction;

Figures 5 and 6 are sectional and part-sectional views respectively illustrating alternative forms of a further modification; and 40

Figure 7 is a sectional view of a portion of a valve tappet illustrating a further modification.

In describing the invention reference is made to the preferred forms thereof illustrated in the accompanying drawings and specific language is employed. It will nevertheless be understood that no limitation of the scope of the invention is thereby intended and that various further modifications and alterations of the illustrated structure are contemplated. 45

In the arrangement shown in Figure 1 of the drawings, it will be observed that the valve stem is indicated at 12, the stem being provided with 50

the usual spring seat 13 against which abuts the lower end of a coil spring 14, the latter serving to retain the head of the valve (not shown) on the valve seat in the conventional manner. The 5 valve is reciprocated on rotation of the cam shaft 16 which is provided with a radial cam 17, thrust being transmitted from the cam to the valve stem by means of a cam follower or tappet indicated generally at 20, the tappet being 10 supported for reciprocating movement in a guide opening 19 formed in the stationary member 21, the latter preferably constituting a part of the engine block. It will be appreciated that the structure thus far described is quite conventional 15 and may assume other forms, the novel features of this embodiment of the invention residing in the construction of the valve tappet 20.

This valve tappet is shown as comprising a generally cylindrical casing 24, which slidably 20 engages the walls of the opening 19 and which is preferably retained against rotative movement by means of a lug 25 which may be formed integrally with the casing 24 and which is received within the laterally extending slotted portion 26 25 of the member 21. The structure whereby adjustment of the tappet to take up clearance is automatically effected is located in what may be described for convenience as the upper portion of the casing 24, and thus the casing may be 30 provided with an anti-friction device for engaging the radial cam 17 without increasing the conventional length of the tappet and consequently without redesigning to alter the spacing between the cam shaft and the valves ordinarily employed 35 in internal combustion engines.

This anti-friction means may take the form of a roller 28 provided with a bushing 29 which is journaled for rotation on a pin 30, the latter being secured in position in the lower end 31 of 40 the casing 24 which is reduced in width for the purpose of more readily accommodating the roller.

Clearance in the valve actuating mechanism is eliminated by means which provides for automatically increasing the effective length of the valve tappet 20, and in the form of the invention shown in Figure 1 this means is located wholly within the upper end of the casing 24. Thus a cylinder 33 having a diameter substantially 45 smaller than the internal diameter of the casing 24 is provided with a base portion 34, the latter being received within the cylinder and seating on an annular abutment 35 formed within the casing. A piston 36 slides within the cylinder 33 and at its upper end carries and is preferably 50 formed integrally with a valve stem engaging member 38, the latter having a sliding fit within the casing 24 and being retained therein by means of an expansion ring 39 or the like which seats 55 in a groove formed internally of and at the upper end of the casing. The member 38 is provided with an upwardly directed, centrally disposed boss 40 for engaging the lower end of the valve stem 12.

60 A coil spring 42 surrounds the cylinder 33 and acts between the member 38 and the base 34 of the cylinder, thus serving to retain the cylinder in position within the casing and in engagement with the abutments 35 and also to urge the member 38 and piston 36 upwardly, or outwardly of the cylinder 33 to thereby expand the tappet. An 65 annular flexible element, preferably in the form of a metallic bellows 43, surrounds the cylinder 33 and spring 42 and is secured at its upper 70 and lower ends respectively to the member 38 and

the base 34 of the cylinder 33. The manner in which the bellows 43 may be secured in position may vary, it being necessary, however, to provide a fluid-tight seal. Welding or soldering may be resorted to for this purpose. 5

A valve plate 45 is disposed within the cylinder 33 and is arranged to cooperate with the lower end of the piston 36 to close a passage 46 formed in the latter, a coil spring 48 being positioned in the lower end of the cylinder 33 to normally hold 10 the valve plate 45 in seated position. Obviously this arrangement constitutes a simple form of one-way valve permitting fluid flow into but not out of the lower end of the cylinder 33, and other types of one-way valves may be employed 15 in lieu of that shown. The passage 46 communicates through ports 49 formed in the lateral walls of the piston 36 with the reservoir defined by the interior of the bellows 43, the member 38, and the base 34 of the cylinder 33, this reservoir being designated by the numeral 50.

The base 34 of the cylinder is provided with a transversely extending passage 51 and axially directed passages 52 and 53 intersecting the passage 51, the passage 52 communicating with the 25 interior of the cylinder 33 and the passage 53 communicating with the reservoir 50. A tapered pin 54 may be driven into the passage 51 to close off the passages 52 and 53 and complete the sealing of the reservoir 50 and the parts with which 30 this reservoir is in communication.

The piston 36 preferably fits somewhat loosely within the cylinder 33; at least there is sufficient play to permit of seepage of liquid past the piston. Alternatively, a restricted by-pass may be 35 provided to permit slow discharge of liquid from the closed end of the cylinder 33 into the reservoir 50. This is essential in order that expansion of liquid within the cylinder may be permitted without consequent upward movement of 40 the piston as the temperature of the engine and associated parts increases during operation.

Preferably the boss 40 on the member 38 is dimensioned to receive a cup-shaped retainer 56 beneath which may be positioned one or more 45 shims 57, the retainer 56 directly engaging the lower end of the valve stem. Thus with the parts in the position indicated in Figure 1 of the drawings, the upward thrust imparted by the cam 17 to the roller 28 on rotation of the cam shaft will be transmitted through the tappet 20 to the valve stem 12 for the purpose of periodically raising the valve from its seat. 50

Assuming that the reservoir 50 and the interior 55 of the cylinder 33 are completely filled with liquid, the spring 42 urges the member 38 outwardly and maintains the retainer 56 in engagement with the valve stem. Owing to the incompressibility of the liquid, the piston 36 will be prevented from moving downwardly within the cylinder 33, at least during the short period of 60 time during which an impulse is actually applied to the tappet by the cam 17, and the tappet will function as a rigid unit to transmit thrust to the valve stem 12. As the engine heats up during the initial period of operation, the liquid within the closed end of the cylinder 33 will expand and will seep out into the reservoir 50 past the piston 36 and through the ports 49. Expansion of liquid within the reservoir 50 is of course permitted by 65 the flexible bellows 43 which is deformed to the extent required to accommodate the increased volume of liquid which is present at the higher 70 temperature.

As the moving parts of the valve operating 75

mechanism wear, ordinarily tending to develop play and clearance between the tappet and the valve stem 12, the spring 42 forces the member 38 and piston 36 further outward to prevent the establishment of any clearance, flow of liquid past the valve 45 into the closed end of the cylinder 33 being permitted during this adjustment of the parts.

It is essential that the parts be assembled in such manner as to exclude air from the reservoir 50 and other liquid filled portions of the device. Obviously if air enters the closed end of the cylinder 33, even in extremely small quantity, downward movement of the piston 36 accompanied by compression of this air is likely to occur on the transmission of thrust through the tappet, thus defeating the purpose of the fluid system. If air is present at any point in the fluid system, for instance in the reservoir 50, it is likely that an emulsion of air and liquid will form which will result eventually in the introduction of air into the closed end of the cylinder 33 in the form of minute bubbles. The preferred method of assembly whereby these difficulties are avoided is substantially as follows.

The valve plate 45 and the spring 48 are first assembled in the lower end of the cylinder 33 and the spring 42 is assembled about the cylinder. The piston 36 is then introduced in the cylinder 30 and the bellows 43 is secured to the member 38 and to the base 34 of the piston to completely enclose the reservoir 50. The passages 51, 52, and 35 53 are open so that a suitable liquid, for instance oil, glycerin, or the like, can be introduced in the passage 53, pressure being applied if necessary to open the valve 45, and when the reservoir 50, the passage 46, and the closed end of the cylinder 33 have been completely filled with liquid, excess liquid will flow out of the passage 52, the air having all been discharged through this passage since there are no pockets within the system which might permit trapping of air. The pin 54 is now inserted to close the passages 52 and 53, the assembled piston and cylinder are placed 40 within the casing 24, and the locking ring 39 is seated in the upper end of the casing. It will now be observed that the axial movement of the piston is definitely limited in either direction and the assembled device constitutes a self-contained 45 unit which is in readiness for insertion as such in the tappet guide opening 19. While the dimensions of the casing 24 and the over-all length of the entire tappet are comparable to the dimensions of non-adjustable tappets, so that the present unit may be employed as a replacement unit 50 without redesign of conventional valve actuating mechanism, the length of the tappet as measured between the cam engaging portion of the roller 28 and the remote end of the boss 40 when the member 38 is in engagement with the locking ring 39 is preferably less than the spacing between the lower end of the valve stem 12 and the dwell portion of the cam 17. The retainer 56 is then applied to the boss 40, a sufficient number of shims 55 57 being placed beneath the retainer, as determined by actual measurement, to depress the piston 36 to the extent necessary to provide a small clearance, say about .002 inch, between the member 38 and the locking ring 39 when the tappet 60 is in assembled position with the engine valve engaging the valve seat. It will be observed that by following this procedure, substantially the same degree of compression will be applied to each of the springs 42 of the several tappets employed in a given engine regardless of variation in

dimensions of the valve actuating mechanism resulting from conventional manufacturing tolerances. Thus uniformity of action of the several valve tappets is secured and each tappet is capable of expanding to the extent which will be required during the normal life of the engine. It is of course obvious that if excessive wear takes place, further adjustment can be made by the introduction of additional shims 57 under the retainer 56, the retainer and the shims constituting in effect a manually adjustable device which may be regulated wholly independently of the automatic adjustment and which may therefore be substituted by other types of manually adjustable devices, for instance the more conventional threaded element commonly employed in manually adjustable tappets.

While care is preferably taken in the construction of the tappet to ensure that operation of the valve mechanism will not be affected adversely by variation in engine temperature, it may be advisable to provide for the cooling of the tappet guides so that several tappets of an engine may acquire substantially the same temperature in order that uniform results may be achieved and so that none of the valve tappets will be subjected to an excessive temperature. For this purpose it is proposed to cool the tappet guides by circulating the water of the engine cooling system past and in close proximity to the guides. The manner in which this may be effected is indicated in Figure 3 in which is shown a passage 59 for water leading from and communicating with the interior of the engine water pump 60, this passage extending rearwardly through the engine block and upwardly at the rear end thereof and passing forwardly in the tappet supporting member 21, being in communication with the water jackets 61 surrounding each of the tappet guides 19 and discharging at the forward end of the cylinder block into the engine cooling system. Obviously the details of this cooling arrangement may be varied to a considerable extent to suit the engine structure to which it is applied and to secure efficient circulation of cooling water about the tappet guides.

While Figure 4 illustrates a modified form of the arrangement shown in Figures 1 and 2, the construction is in general quite similar. Thus the tappet 20' comprises a casing 24' carrying a cam engaging roller 28', the moving parts of the tappet being located in the upper end of the casing. These moving parts include a piston 36' which slides with a slight clearance in a cylinder 33', the piston being formed at its upper end to provide an annular member 38' and an outwardly directed boss 40'. The piston 36' is urged outwardly of the cylinder by means of the coil spring 42', the spring being received within the piston. The valve plate 45' and the coil spring 48' which normally retains the valve in seated position against the passage 46' are also disposed within the piston, it being observed that the lower end of the cylinder is initially and completely closed and thus, with the exception of such seepage of liquid as occurs past the piston, liquid may be introduced into the cylinder only through the passage 46' and past the valve plate 45'.

The cylinder 33' is provided with a circumferential flanged portion 34' which is arranged to seat against an annular abutment 35' formed interiorly of the casing 24'. A flexible diaphragm 43', preferably of the bellows type, extends between and is secured to the member 38' of the piston and the flange 34' of the cylinder to seal

the fluid system and to provide a reservoir 50'. A second flexible bellows 44 is secured to the lower side of the cylinder flange 34', the lower end of the bellows 44 being closed by means of a plate 47, whereby a second fluid reservoir 55 is formed. Communication is afforded between the reservoirs 50' and 55 by one or more ports 58 formed in the cylinder flange 34'. The reservoir 50' also communicates with the valve controlled passage 10 46' through a transverse passage 49' in the upper end of the piston, and initial access to the valve controlled passage is also afforded by a passage 62 extending through the boss 40' and by a passage 63 extending through the member 38'. Passages 62 and 63 are closed after the filling of the fluid system by plugs 65 and 66 respectively. A locking ring 39' provided in the upper end of the casing 24' retains the moving parts of the tappet in assembled position within the casing. 20 In operation this form of tappet is quite similar to that first described and is quite compact both axially and radially so as to permit of the use of the casing 24' having dimensions comparable with those of conventional manually adjustable tappets. The fluid system is filled with liquid through the passage 62, flowing downwardly into the cylinder past the valve plate 45' and through the ports 58 into the reservoir 55, air being discharged through the passage 63. When the system is completely filled, the plugs 65 and 66 are forced in to seal the system.

The flexible bellows 44 is readily extensible in an axial direction to accommodate expansion of fluid within the system as the engine temperature increases. The bellows 43' functions principally to permit inward and outward movement of the piston 36' and associated parts, lateral expansion of the bellows 43' in response to increased temperature being thereby rendered unnecessary 35 with resultant avoidance of application of unnecessary stress to either bellows, increased uniformity of action resulting.

In the modified form of the invention shown in Figures 5 and 6 of the drawings, a general radially disposed flexible element 68 is employed, this element being preferably constructed in the form of a metallic disk having annular corrugations so as to permit of slight axial flexure to accommodate the increased volume of liquid resulting from increased temperature. The construction is otherwise quite similar to that illustrated in Figures 1, 2, and 4, with the exception that the casing 24'' and the cylinder 33'' are preferably formed integrally. At its upper end the casing is provided with an annular flange 69 on which is seated and secured, in such manner as to form a fluid seal, an annular plate 70. The diaphragm 68 is secured to the plate 70 by crimping over the latter, as indicated at 72, the inner circumference of the diaphragm being received in an annular slot 73 formed in the member 38'' which is in turn formed integrally with the piston 36'', pressure being applied axially of the member 38'' to clamp the diaphragm 68 securely in the slot 73. The plate 70 is also formed with a plurality of inwardly directed lugs 75 which cooperate with an annular flange 76 formed on the member 38'' to limit outward movement of the latter and of the piston 36''. The coil spring 42'' surrounds the cylinder and acts between the latter and the member 38'' to normally urge the piston outwardly, and a one-way valve comprising a valve plate 45'' and a spring 48'' prevents flow of liquid out of the cylinder except to the extent that seepage is per-

mitted past the piston as in the first described embodiments.

The casing 24'' is provided with two passages 78 and 79 through which the system may be filled with liquid and air completely discharged therefrom in a manner quite similar to that hereinbefore described, these passages being both closed after filling by the insertion of a plug 80 in the passage 79. Ports 49'' formed in the piston 36'' afford communication between the reservoir 50'' and the interior of the cylinder past the valve plate 45''.

For the purpose of reducing the weight of the tappet shown in Figure 5, the lower end of the casing 24'' may be apertured as indicated at 82 15 and the casing may be provided with a closed end 83 for direct engagement with the cam shaft in the conventional manner. Since, however, the moving parts of the construction illustrated in Figure 5 including the fluid system are extremely 20 compact in an axial direction, it is possible to employ anti-friction means for engaging the cam, and this alternative arrangement is illustrated in Figure 6 in which the roller 28'' is shown as mounted in a manner similar to that 25 described in connection with the other embodiments of the invention.

In Figure 7 a further modification is shown which is closely related to the form of the invention shown in Figure 1, similar reference 30 characters being employed to designate similar elements with the exception of a bellows 85 and a coil spring 86. The bellows 85 in this view is ribbed helically rather than circumferentially and receives within the recesses thus provided 35 the coil spring 86 which is of corresponding helix. With this construction it is possible to employ a coil spring of greater diameter without increase in the diameter of the casing 24, the stress applied to the spring being thereby reduced with resultant increase in life.

It will be observed that with the exception of the modified form of the invention shown in Figure 5, the several constructions illustrated in the drawings involve the employment of a fluid system 45 for expanding the tappet, this fluid system being independent of the outside cylindrical casing of the tappet. In other words, pressure developed within the fluid system is not transmitted directly to the walls of the tappet casing. This is 50 an important feature since it is desirable to reduce the total weight of the tappet to a minimum and thus to avoid the employment of outer casing walls of substantial thickness. If a thin wall is employed and fluid pressure is applied to the wall, 55 the casing is likely to expand with the result that the tappet will seize in the guide opening 19. By constructing the fluid system as a unit separate from the outer casing of the tappet, this expansion and seizure is avoided and thin casing walls 60 can nevertheless be employed.

In all of the forms of the invention hereinbefore described it is preferred that a separate manually adjustable device be associated with the tappet, and similar devices have been illustrated 65 in the drawings, but it will be appreciated that this feature may be discarded if desired and reliance placed solely on the automatically operating portion of the tappet to eliminate clearance in the valve actuating mechanism. It will also 70 be obvious that while the construction of the working parts of the tappet is preferably such as to permit of the use of an anti-friction cam engaging roller together with means for preventing the tappet from rotating during operation, such 75

a roller may be eliminated together with its attendant advantages and reliance be placed on the more conventional arrangement shown in Figure 5 and employing a casing having a closed end.

5 The invention is of course useful as a take-up device for valve actuating mechanism whether embodied in a tappet or whether employed in some other relation to the mechanism. A further possible use of the device is illustrated, for 10 instance, in the application of Van Ranst Serial No. 618,653, filed June 22, 1932. It is also clear that under some circumstances it is possible to omit the coil spring which tends to expand the device and to rely solely on the action of the 15 flexible bellows for this function. Thus in Figures 1, 2, and 4 in which an axially arranged bellows is connected between the cylinder and piston, this bellows may be made sufficiently flexible and elastic so that when initially compressed axially 20 during assembling, an outward thrust will be exerted on the piston sufficient to ensure that clearance will be properly taken up. This feature is not claimed specifically herein but is dealt with more particularly in my copending application 25 Serial No. 26,483, filed June 13, 1935.

Having thus described the invention, what is claimed as new and desired to be secured by Letters Patent is:

1. A valve tappet operable automatically to 30 take up clearance comprising a generally cylindrical casing, a cam engaging roller, means supporting said roller for rotation on the axis thereof in one end of said casing, and means carried by the other end of said casing for transmitting 35 thrust to a poppet valve, said last named means including a valve stem engaging member supported within said casing for sliding movement in an axial direction, a cylinder mounted in fixed position in said casing and having one closed end, 40 a piston carried by said member and movable in said cylinder, said piston and cylinder being constructed to provide a restricted fluid passage from one side to the other side of said piston, one-way valve means permitting fluid flow into said cylinder only, spring means urging said piston and 45 member outwardly of said cylinder and away from said roller, means acting between said casing and member to limit outward movement of the latter, and means including a flexible dia- 50 phragm acting in conjunction with said cylinder and said member to provide a sealed reservoir completely filled with liquid and communicating with the open end of the cylinder, said flexible diaphragm yielding to compensate for expansion of fluid and to permit outward movement of said member to eliminate clearance between said member and valve stem.

2. In valve operating mechanism, the combination 55 with a valve tappet having a generally cylindrical casing, of means supporting said casing for reciprocation, guide means acting between said first named means and said casing to prevent rotation of the latter, a cam engaging roller, means supporting said roller for rotation on the axis thereof in one end of said casing, and means 60 carried by the other end of said casing for transmitting thrust to a poppet valve, said last named means including a valve stem engaging member supported within said casing for sliding movement in an axial direction, a cylinder mounted 65 in fixed position in said casing and having one closed end, a piston carried by said member and movable in said cylinder, said piston and cylinder being constructed to provide a restricted fluid 70 passage from one side to the other side of said

piston, one-way valve means permitting fluid flow into said cylinder only, spring means urging said piston and member outwardly of said cylinder and away from said roller, means acting between said casing and member to limit outward movement of the latter, and means including a flexible diaphragm acting in conjunction with said cylinder and said member to provide a sealed reservoir completely filled with liquid and communicating with the open end of the cylinder, said flexible diaphragm yielding to compensate for expansion of fluid and to permit outward movement of said member to eliminate clearance between said member and valve stem.

3. A valve tappet operable automatically to 15 take up clearance comprising a generally cylindrical casing, a cam engaging roller, means supporting said roller for rotation on the axis thereof in one end of said casing, and means carried by the other end of said casing for transmitting 20 thrust to a poppet valve, said last named means including a valve stem engaging member supported within said casing for sliding movement in an axial direction, a cylinder mounted in fixed position in said casing and having one closed end, 25 a piston carried by said member and movable in said cylinder, said piston and cylinder being constructed to provide a restricted fluid passage from one side to the other side of said piston, one-way 30 valve means permitting fluid flow into said cylinder only, spring means urging said piston and member outwardly of said cylinder and away from said roller, means acting between said casing and member to limit outward movement of the latter, and means including a flexible dia- 35 phragm of the metallic bellows type arranged generally coaxially of and about the cylinder and acting in conjunction with said cylinder and said member to provide a sealed reservoir completely 40 filled with liquid and communicating with the open end of the cylinder, said flexible diaphragm yielding to compensate for expansion of fluid and to permit outward movement of said member to eliminate clearance between said member and valve stem.

4. A valve tappet operable automatically to 45 take up clearance comprising a generally cylindrical casing, a cam engaging roller, means supporting said roller for rotation on the axis thereof in one end of said casing, and means carried by the other end of said casing for transmitting 50 thrust to a poppet valve, said last named means including a valve stem engaging member supported within said casing for sliding movement in an axial direction, a cylinder mounted in fixed 55 position in said casing and having one closed end, a piston carried by said member and movable in said cylinder, said piston and cylinder being constructed to provide a restricted fluid passage from one side to the other side of said piston, one-way 60 valve means permitting fluid flow into said cylinder only, spring means urging said piston and member outwardly of said cylinder and away from said roller, means acting between said casing and member to limit outward movement of the latter, and means including a flexible dia- 65 phragm formed as a metallic disk having annular corrugations and acting in conjunction with said cylinder and said member to provide a sealed reservoir completely filled with liquid and communicating with the open end of the cylinder, said flexible diaphragm yielding to compensate for expansion of fluid and to permit outward movement of said member to eliminate clearance between said member and valve stem.

5. A valve tappet operable automatically to eliminate clearance in the valve actuating mechanism, said tappet comprising a casing having dimensions comparable to those of standard 5 manually adjustable tappets, and means associated with said casing operable on occurrence of clearance in the valve actuating mechanism to increase the effective length of the tappet, said means including a sealed fluid system completely 10 filled with liquid for resisting axial compression of said tappet and comprising a cylinder and piston located within said casing, and elastic means acting yieldingly to lengthen the tappet, said elastic means being ineffective to oppose the seating of the valve by the valve spring, said elastic 15 means being interposed between said casing and cylinder and surrounding the latter.
6. A valve tappet operable automatically to eliminate clearance in the valve actuating mechanism, said tappet comprising a casing having dimensions comparable to those of standard 20 manually adjustable tappets, and means disposed within said casing operable on occurrence of clearance in the valve actuating mechanism to increase the effective length of the tappet, said means including a sealed fluid system completely 25 filled with liquid for resisting axial compression of said tappet and comprising a cylinder and piston located within said casing, and elastic means 30 acting yieldingly to lengthen the tappet, said elastic means being ineffective to oppose the seating of the valve by the valve spring, said elastic means comprising a coil spring surrounding said cylinder and piston and acting between the latter to urge 35 the piston outwardly.
7. A valve tappet operable automatically to eliminate clearance in the valve actuating mechanism, said tappet comprising a casing having dimensions comparable to those of standard 40 manually adjustable tappets, and means associated

with said casing operable on occurrence of clearance in the valve actuating mechanism to increase the effective length of the tappet, said means including a sealed fluid system completely 5 filled with liquid for resisting axial compression of said tappet and comprising a cylinder and piston located within said casing, elastic means acting yieldingly to lengthen the tappet, said elastic means being ineffective to oppose the seating of the valve by the valve spring, said elastic means 10 comprising a coil spring surrounding said cylinder and piston and acting between the latter to urge the piston outwardly, and expansible sealing means comprising a bellows disposed within said casing and surrounding and secured at its 15 ends to said piston and cylinder.

8. In an automatically expansible valve take-up device, the combination with a piston, of a unitary member affording a cylinder portion for the reception of said piston, said cylinder portion 20 and piston constituting a part of a closed fluid system resisting compression of said device, elastic means acting between said member and said piston to yieldingly expand said device, means for completely sealing said system, and a generally 25 cylindrical casing, said fluid system being housed within and readily removable as a unit from said casing without discharge of liquid from the system.

9. In an automatically expansible valve take-up device, the combination with a closed fluid system resisting compression of said device, of means acting to yieldingly expand said device, means for completely sealing said system, and a generally 30 cylindrical casing, said fluid system being housed within and removable as a unit from said casing without discharge of liquid from the system.

FRANK C. BEST. 40
